CLAIM

The ornamental design of a networking device, as shown and described.

DESCRIPTION

FIG. 1 is a perspective view of the networking device.

FIG. 2 is a front view of the networking device.

FIG. 3 is a right view of the networking device.

FIG. 4 is a left view of the networking device.

FIG. 5 is a back view of the networking device.

FIG. 6 is a top view of the networking device; and,

FIG. 7 is a bottom view of the networking device.
